UNITED STATES PATENT OFFICE

FRANCIS E. OGILVIE, OF UNIVERSITY, VIRGINIA, ASSIGNOR OF ONE-HALF TO WILLIAM H. SAWYERS, OF HINTON, WEST VIRGINIA

PARKING DEVICE

Application filed September 6, 1930. Serial No. 480,224.

My present invention has reference to the means for regulating the privilege of street parking of automobiles and like vehicles and is designed for use by cities, towns, villages, and other civic corporations as well as by private persons and corporations and among the objects of the invention is the provision of a parking device for controlling, regulating and limiting the parking of vehicles in legalized and specified areas; for relieving the congestion incident to the promiscuous and unnecessary parking of vehicles in specified areas; for the detection of violations of parking regulations and for the collection of revenue for the use of authorized parking space.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a front elevation of my improved parking device, looking toward the face thereof opposite the space in which a car is to be parked.

Figure 2 is a similar view looking toward the opposite face of the device.

Figure 3 is a side elevation with parts broken away and parts in section.

Figure 4 is an end view with parts broken away and parts in section.

Figure 5 is an elevation with the cover plates removed.

Figure 6 is a sectional view approximately on the line 6—6 of Figure 3.

Figure 7 is a perspective view of the plunger.

Figure 8 is a similar view of the trip for the spring latching member.

Figure 9 is a similar view of the means employed for permitting of the resetting of the device before the time limit for parking has expired.

In municipalities the parking spaces or designated legalized streets or parking areas are indicated by markers arranged upon weighted posts. Cars parking in such spaces or zones either occupy too large or too small a space. In the first instance, they prevent other cars from parking and in the latter instance frequent damage results to the car leaving the parking spaces by contacting with cars in the front and to the rear thereof. The cars are parked at different intervals of time and it is a matter of great difficulty for the officers of the law to have knowledge of the time allowed the several parked cars. The result of this is the chalking of the wheels of cars which occupy parking spaces when he makes his first round. If such cars still occupy the spaces on his next round a ticket is placed on such cars that requires the owners thereof to appear at a traffic court and pay a fine. This involves a hardship and a loss of time upon the part of the owner of the car and likewise a hardship and a loss of time and duty of the officer of the law who is frequently called upon to prosecute the offender. In addition to this the municipality receives no revenue for parked cars and this loss reverts on the taxpayers, who are in reality the government, municipal or State. While, with my improved parking device it will be necessary that the officer of the law patrol his beat as usual, it will relieve him from the necessity of marking cars and will prove a visible evidence as to whether or not the car is legally or illegally parked, or in other words, that the owner or driver of the parked car has

80
85
90

paid for his parking privilege. Such evidence is also visible to citizens passing the parking device and as it is to their interest that the parking space be duly paid for, they

- 5 may impart their knowledge of infractions of the law to the policeman or other proper authority. The parking device should cut down arrests for parking violations and should speed up traffic by relieving congestion, the time of parking being regulated by the rate of charge. Also, it will be seen, that while my parking device provides means, in the nature of a visible signal which remains in proper position for a determined 15 period of time, say one hour, the occupant of the parking space is privileged to extend his time by simply depositing another coin in the device which, while permitting of the signal momentarily moving to non-signaling 20 position will actuate the parts or mechanism for returning the said signal to signaling position.

In the embodiment of the invention disclosed by the drawings I employ a metal 25 casing 1 which is both dust and water proof. The casing 1 has its main body portion of substantially rectangular formation, its top being arched, as at 2, and one of its corners formed with an extension 3. The casing has 30 what I will term its back open, but this open back is closed by a back plate 4 and a door 5. The back plate 4 and the door 5 are preferably received in notched guide lugs 6, respectively, in the casing 1, and the door is 35 retained closed by a suitable key operated lock whose casing is provided with bolts movable through the ends thereof and into keepers 6 in the reduced corner extension 3 of the casing. It is to be understood that 40 the door 5 must be opened before the back plate 4 can be removed from the casing.

The bottom of the casing is designed to rest on a post, standard or the like which is fixedly embedded in the ground at the curb of a 45 street, roadbed, sidewalk, fence, wall, building or in the ground adjacent any object within the space immediately contiguous to the place where the signals in the parking device are to be displayed. The post or like member 7 has arranged therearound U-bolts 8, and the threaded ends of these bolts enter openings in the inner wall of the corner extension 3 of the casing and the nuts are screwed on the bolts from the inside of the 53 part 3 of the casing. Thus it will be noted that the parking device is firmly supported and cannot be accidentally or surreptitiously removed from its support 7.

It may here be stated that any number of 60 parking devices are arranged in the center of legalized or authorized parking spaces and that one of the parking devices is used by a single car as long as the car occupies such space. Also it is to be stated that the parking spaces may and preferably are denoted by

painted lines or like markings and that the cars may park longitudinally, that is, one directly to the rear of the other or at desired and designated angles.

The front and rear of the casing, adjacent to the arched top thereof, have round alining openings therein, which openings are surrounded by frames 9 for transparent discs, and there is arranged in the casing and designed to be brought opposite the said openings and discs either of a pair of spaced translucent signal discs 10 or 11, both of the signaling discs being mounted upon a substantially V-shaped semaphore arm 12. The disc 10 provides what may be termed a danger signal and is preferably colored red, while the disc 11 provides what may be termed a safety signal and is preferably colored green. When the red colored disc 10 appears in the sight openings in the faces or sides of the casing the parking space is not occupied or if occupied the policeman or pedestrians will be acquainted that the said space is illegally occupied so that proper steps may be taken in apprehending the owner or driver of the vehicle, while when the disc 11 is swung opposite the sight openings, or rather windows 13, (arranged in the frames 9) the officer as well as the pedestrians will have knowledge that the car is entitled to occupy the parking space.

The semaphore carrying arm 12 is fixed on a shaft 14 that is journaled in suitable bearings in the casing 1 and on this shaft 14 there is fixed a wheel 15 which has on its periphery a lug 16. Also fixed on the shaft 14 there is a second wheel or roll 17 that is provided with a peripheral notch 18.

Preferably the shaft 14 is journaled on a plate or frame 19 that is fixed in the casing and in the side plates of which frame there is journaled the ends of a shaft 20 to which is centrally fixed a peripherally grooved segmental member 21.

There is fixed in the groove of the segment 21 which provides the control element of the improvement one end of a cable 22, the second end of the said cable carrying a block or like element 23 arranged for movement in a suitable guide 24 and the purpose of this element will presently be apparent. While the control segment 21 may be electrically operated, it may be turned by a weight attached to a cable which is wound around the shaft 20 or by other means. I have in the showing of the drawings, illustrated the turning or operating means for the segment 21 in the nature of a clockwork. To one of the plates comprising the frame 19 I secure the frame of the clock. The wheels of the clockwork are turned by the usual wound spring 25 and the train of gears operate a comparatively large toothed wheel 26 which is fixed on the shaft 20 and the said shaft is fixed to the segment 21. The clockwork or like turning means for

control segment 21 is such that the segment will be turned thereby to a predetermined distance at a predetermined interval of time, say one hour or more, and the control segment when swung to active position will cause the rewinding of the clockwork, weight or other mechanism.

The semaphore arm 12 is influenced by a spring 27 to normally retain the danger or illegal parking signal 10 in a line with the sight openings in the casing and to normally retain the stop element 16 on the wheel 15 at an angle with respect to the axial plane of the segment 21 and out of but in close proximity to the periphery of the said segment, so that when the segment is turned, in a manner which will presently be described a lug 28 thereon will be brought against the lug 16 and thereby swing the semaphore 12 to bring the signal 11 in a line with the sight openings in the casing.

Any desired means may be employed for latching the semaphore arm 12 to hold the signal in signaling position, such means in the showing of the drawings comprising a catch in the nature of a spring arm 29 that has a right angle offset end 30 that is designed to enter the notch 18 in the wheel 17 which is brought to a position to receive the said end or finger 30 when the semaphore 12 is thus turned. The spring arm 29 has one of its ends secured to an offset portion or block in one of the upper corners of the frame 19. The spring arm of the catch is normally engaged by a dog 31 which extends from a hub 32 that is journaled on a shaft 33 secured between the side plates of the frame 19. The hub 32 has on one of its ends a depending stop finger 34 while its second end is provided with an oppositely directed arm or finger 35 to which is pivoted a link 36 that in turn is pivoted to an arm or finger 37 which projects from a hub 38 that is fixed on a shaft 39. The shaft 39 is journaled through suitable bearing openings in the plates of the frame 19, adjacent one edge of the said plates and a distance below the shaft 33.

There is fixed on the shaft 39 another hub 40 that carries a foot extension 41 that serves as a stop element for a swingable short lever 42, that is journaled on the shaft 39 and the purpose of this arrangement will presently be apparent. The fixed side or face of the casing 1, adjacent to one of the edges thereof, is provided with a coin inlet slot 43. This slot is normally covered by a pivoted shutter 44 which is influenced by a spring to closed position and which is held in such closed position by a stop element 45. Below the coin inlet slot 43 the said side or face of the cover is provided with a longitudinally extending elongated slot or opening 46 and through this opening there is projected the operating handle 47 of a plunger 48. The slot 46, at all times is concealed by a plate that is fixed on

the outer face of the plunger, or the said plunger as disclosed by Figure 7 of the drawings may be in the nature of a cross sectionally T-shaped member and may have its outer face or flange elongated to insure the covering of the slot 46 under all conditions. The plunger 48 has on one of its sides an outstanding lug 49 in the path of contact with the upper face and end of the block 23. The plunger 48 has on one side of the face thereof received in the casing a plate 50 that has its lower edge notched, as at 51, and the upper wall provided by the notch is arranged at an angle. The plate 50, adjacent to the upper end thereof is provided with a substantially rectangular opening 52 for the reception of the swingable finger or lever 42 for a purpose which will hereinafter be apparent.

Secured to the top of the plunger 48 there is a cable 53 trained over grooved wheels or pulleys 54 and 55 journaled adjacent to the top of the casing and likewise adjacent to the sides thereof. The second end of the cable 53 has fixed thereto a weight 55' arranged for movement on a vertically disposed guide 56, and the weight 55' normally holds the plunger in its upper and inactive position.

Communicating with the coin inlet opening 43 there is a coin chute 57. The coin chute is irregularly shaped, that is, the opposite ends thereof are offset angularly from the center body portion thereof and the outlet end of the chute is arranged in a line with the upper angle wall 59 provided by the notch 51 in the plate 50 of the plunger. The lower wall at the outlet of the chute 57 has arranged directly therebeneath a finger 60 that is in the nature of a stop element, the said finger being formed on one end of a rocker arm 61 which is pivotally supported, as at 62, and which has a depending member whose end is offset, as at 63, and arranged directly beneath the plunger 48 and which serves as a stop element for preventing the downward movement of the plunger until swung away from the said plunger. The offset stop element 63 is spaced away from the lower end of the plunger, so that when a coin or the like rests on the finger 60 and is brought against the angle wall 59 provided by the notch 51 in the plunger the downward movement of the plunger will force the coin away from the outlet of the coin chute 57 to deposit the coin in the casing. The rocker lever is influenced by a coil spring to hold its finger in coin obstructing position.

As far as the description has progressed it will be apparent that when the coin or like element rests on the finger 60 and is contacted by the notched edge of the plate 50 and that when a pressure is exerted upon the operating handle 47 the plunger 48, pressing against the coin will depress the finger 60 and rotate the arm 61 on the pivot 62 to swing the offset 63 from under the plunger, thereby unlocking 130

the device to permit of the operation thereof by a further downward movement of the plunger. Such movement will cause the lug or finger 49 to contact with the block 23 to pull on the cable 22 to turn the segment 21 to the right or in a clockwise direction so that the lug 28 will engage with the lug 16 and swing the semaphore arm 12 to bring the signal 11 to signaling position against the influence of the spring 27. The spring catch member will now enter the notch 18 and lock the device in such position.

There is a second lug 65 projecting from the periphery of the control segment 21 and which is spaced a desired distance from the lug 28, while between the arm 37 and the frame 19 there are fixed the ends of a light coil spring 66 for holding the said arm in one position. The swinging of the arm when influenced by the spring is limited by a stop element 67. The safety signal 11 will be held in display position until the operating mechanism for the control segment 21 turns the same in an anti-clockwise direction and brings one of the straight edges of the same against a contact lug 68. The return movement of the segment to its normal position in this direction will cause the operation of an alarm such as a bell which is indicated by the numeral 69 in the drawings. When the segment is thus turned the lug 65 will be brought into engagement with the finger 34 on the hub 33, swinging the said hub to cause the dog 31 thereon to exert a pressure against the flat spring arm 29 of the catch member 30, bringing the said catch out of the notch 18 in the roll or wheel 17 and permitting the spring 27 to swing the semaphore to again bring the danger or illegal parking signal 10 to signaling position. In the meantime the weight 55 has returned the plunger to its upper normal position. The device now clearly discloses the fact that the time limit of the parking space paid for by the automobilist has expired. In the event of the automobilist desiring to extend the time of parking his machine for a greater period than he is normally allowed and also before the time limit of his parking has expired, that is, before the segment 21 has fully returned to its initial position under the influence of its turning mechanism, another coin is deposited. The spring catch 30, it is to be understood, is still in the notch 18 and to release the same in a manner as heretofore described and, that is, through the medium of the lug 65 on the segment 21, the said segment must have returned to its initial position, that is, the lug 28 thereof must be brought against the stop element 68. The upward movement of the plunger through the medium of the weight 55' will cause the same to contact with the finger 42 to swing the said finger or lever into the slot or opening 52. The coin has been de-

posited to operate the coin contact element 60 and the plunger stop element 63 which permits the plunger to be moved downwardly. This movement will bring the upper wall of the slot or opening 52 into contact with the lever 42, causing the same to engage with the stop element 41 on the turnable shaft 39, which latter swings the arm or finger 29 which imparts a like movement to the arm 35 on the hub 32 and brings the dog 31 against the body 29 of the spring catch 30, causing the catch to move out of the notch 18 and momentarily permitting the spring 27 to bring the danger signal 10 opposite the sight openings in the casing but the lug 49 on the plunger having again engaged with the block 23 will turn the control segment 21 to cause the lug 28 thereon to again contact with the lug 16 on the wheel that is fixed to the shaft 14 and again swing the semaphore arm to bring the safe or legal signal 11 in signaling position and causing the device to be latched by the spring influenced member 30 and the parts to operate in the same manner as previously described.

The coins will flow into the reduced portion 3 of the casing and the descent of the weight 55' will contact with means for operating a disc recorder 56', whereby the number of times which the device has been operated and likewise the number of coins that should be received in the device are accurately recorded. Obviously any suitable recording means may be provided and may be operated in a different manner from that just described.

The construction and operation of the improvement will, it is thought, be understood and appreciated by those skilled in the art to which the invention relates. In addition to the advantages of the device heretofore set forth, the improvement will tend to eliminate the aimless "jay-rider" who has no definite place to go, and who usually over-parks if there is no immediate check-up it will spot the chronic "parking-hog," permit unmolested parking rights for a very modest fee, add to the revenue of the municipality in which it is installed and may readily be electrically wired to a central station to indicate the parking spaces occupied either legally or illegally.

It is within the province of this invention to dispense with the illegal signal lens 10, should it be found desirable as a clear light through the windows in the casing will indicate that the parking space is open for parking or that the said space is illegally occupied. Also the device may be electrically illuminated during the night time. Also tokens, keys or the like purchased from the proper authorities may be employed in lieu of a coin for permitting the downward movement of the plunger.

Having described the invention, I claim:

1. A parking device for vehicles, fixed in a line with the center of the parking space and including a casing having windows and having a reduced corner extension, a fixed post contacting with the bottom of the casing proper and with the inner wall of the extension, and means engaging the post and concealed in the casing extension for locking the casing thereon, said casing having one of its sides removed and having one of its sides open, a side plate for closing said openings, a normally locked door for closing the extension, a signal pivotally supported in the casing, spring means for holding the signal away from the windows, a member pivoted in the casing, power storing means for the member for normally holding the same in one position, plunger means for swinging the member to a second position, means between the member and the signal for swinging the signal to signalling position when the member has been influenced by the plunger, a spring influenced catch, means operated by the member for normally holding the latch in unlatching position and permitting the latch to engage with the signal to hold the signal in signalling position and said latching means being releasable by the member when the said member has been returned by the power means to its initial position.
2. A parking device for vehicles, fixed at a parking space and including a casing having windows, a signal in the casing, spring means for normally holding the signal away from the windows, a pivotally supported control member, power means influencing and normally holding the member in one position, a finger operated plunger, weighted means normally holding the plunger in one position, means between the plunger and the control member for turning the said member against the influence of the power means when the plunger is manually operated, contact elements between the control member and the signal for throwing the signal opposite the windows to signalling position, means also operated by the member for latching the signal in signalling position, means actuated by the member for releasing the latching means for the signal when the plunger is returned to its initial position and when said member has been turned by the power means to its initial position to permit of the signal being moved by the spring means therefor to unsignalling positions.
3. A parking device for vehicles, including a casing having windows, a signal having a shaft journaled in the casing, spring means for swinging the signal away from the windows, an element on the shaft carrying a lug, another element on the shaft having a notch, a pivotally supported segmental control disc having spaced lugs thereon, power mechanism for holding the segment in one position, a flexible element on the segment having a block fixed thereto, a hand actuated vertically movable plunger, weighted means influencing the plunger to an upward position, a lug on the plunger arranged over the block and designed to contact therewith when the plunger is moved downwardly, to cause the turning of the segment against the influence of the power means and to bring one of its lugs into contact with the lug on the shaft of the signal for swinging the signal opposite the windows to signal position, a spring influenced latch, means operated by the second lug on the segment for normally holding the latch out of engagement with the notch in the element on the signal shaft and for releasing said shaft to permit of the same being received in the notch when the first-named contact on the segmental member has thrown the signal to signalling position, and the second lug on the segmental member designed to operate the latching means to release the latch when the segmental member has been returned by the power means to its initial position.
4. A parking device for vehicles, which includes a casing, having its opposite faces provided with alining openings, a signal, a shaft journaled in the casing and to which the signal is fixed, spring means for swinging a signal away from the windows, an element on the shaft carrying a lug, another element on the shaft having a notch, a pivotally supported segmental control disc having spaced lugs therein, power mechanism for holding the segment in one position, a flexible element on the segment having a block fixed thereto, a hand operated vertically movable plunger having a lug that is normally disposed above the block, weighted means for sustaining the plunger in raised position, and said plunger when moved against the influence of said weighted means designed to have the lug thereon contact with the block to turn the segment against the influence of the power means to bring one of its lugs into contact with the lug on the shaft of the signal for swinging the signal opposite the windows, a spring influenced latch, means operated by the second lug on the signal for normally holding the latch out of engagement with the notch in the element on the signal shaft and for releasing the latch to permit of the same being received in the notch when the first-named lug on the segmental member has thrown the signal to signalling position and the second lug on the segmental member is brought by its power means to release the latch, and to likewise return the segmental member to its initial position, and means operated by the segmental member for sounding an alarm when returned to its said initial position.
5. A parking device for vehicles, including a casing having windows, a signal journaled on a shaft in the casing, spring means for

swinging the signal away from the windows, an element on the shaft carrying a lug, a second element on the shaft carrying a notch, a pivotally supported segmental control disc having spaced lugs thereon, power mechanism for influencing the segmental member to one position, a stop member for holding the said member in such position, a block flexibly secured to the segmental member, a hand operated vertically movable plunger having a lug that is normally disposed over the block, weighted means for sustaining the plunger in one position and for permitting the movement of the plunger in a downward direction to cause the lug on said plunger to contact with the block to turn the segment against the influence of the power means and to bring one of its lugs in contact with the lug on the shaft of the signal for swinging the signal opposite the windows, a spring influenced latch, means operated by the second lug on the segment for normally holding the latch out of engagement with the notch in the element on the signal shaft and for releasing said latch to permit of the same being received in the notch when the first named contact on the segmental member has thrown the signal to signalling position, and the second lug on the segmental member designed to operate the latch holding means to release the latch, when the segmental member has been returned by the power means to its initial position, means operated by the segment for sounding an alarm, and recording means actuated by the plunger for recording the movement of the plunger in a downward direction.

6. A parking device for vehicles fixed in a line with the center of a parking space including a casing having windows in the opposite sides thereof, a substantially V-shaped semaphore arm, a shaft journaled in the casing, and on which the semaphore arm is fixed, differently colored translucent discs on the arms to indicate respectively legal and illegal parkers, spring means for influencing the arm to bring the illegal signals opposite the windows, spaced wheels on the shaft for the arm, one having a lug and the other having a notch, a pivotally supported segmental member in the casing having spaced lugs on the periphery thereof, power storing means for influencing the signal member to one position, stop means for holding the signal member in such position, a spring influenced latch, a pivoted member having a dog to rest on the latch, and a stop finger, which latter is in the path of engagement with one of the lugs on the shaft, a normally concealed hand operated vertically movable plunger, weighted means for influencing the plunger in an upward direction, a lug on one face of the plunger, and an element carried by the segmental member over which the lug is normally arranged, and said plunger having an

opening adjacent its upper end, a shaft having a freely mounted finger thereon movably received in said opening, a stop element fixed on the shaft for holding the finger from movement in one direction, a second finger fixed on the shaft, a spring for influencing the second finger in one direction, and a link connection between said second finger and the dog carrying member, all as and for the purpose set forth.

In testimony whereof I affix my signature.

FRANCIS E. OGILVIE.
